UNITED STATES PATENT OFFICE.

CHARLES E. FERRELL, OF OKLAHOMA, OKLAHOMA.

VEGETABLE-BINDER.

1,190,392.

Specification of Letters Patent. Patented July 11, 1916.

Application filed April 8, 1913. Serial No. 759,666.

To all whom it may concern:

Be it known that I, CHARLES E. FERRELL, a citizen of the United States, residing at Oklahoma, in the county of Oklahoma and State of Oklahoma, have invented a new and useful Vegetable-Binder, of which the following is a specification, reference being had to the accompanying drawings.

This invention relates to a machine for binding and tying bunches of vegetables, such as onions, radishes, spinach, turnips and so forth; cutting away the surplus tops, and counting the bundles.

It is an object of the invention to produce these operations in their proper order automatically by power and to embody the invention in a simple and practical machine.

Other objects of the invention will appear from the further reading of the following specification:

The machine shown in the drawings is one of the practical embodiments of the invention, and while a clear, exact description of the machine will follow, it may be here stated, that, so long as the spirit of the invention is maintained, various machines may be constructed whereby to embody that invention.

Referring to the drawings, Figure 1 is an elevation of a machine, showing a needle, a knotter, cutters, and means for actuating the same, a cord box and cord tensioning device, and other parts desirable to a complete machine. Fig. 2 is a partly disassembled plan view. Fig. 3 is an elevational view of a set of cutters. Fig. 4 is a plan view thereof, with a gage mechanism associated therewith. Fig. 5 is a perspective view of a knotter. Fig. 6 is a detail view of an element thereof, and Fig. 7 is a partly sectional view of said knotter.

In these views similar characters of reference will indicate similar parts.

A general framework, comprising a stand, which may be employed or omitted, and which is designated in a general way by standards 8 and 9, a base 10, and a cross bar 11. This framework supports a table 12 to which is secured arms 13 and 14 in which is journaled a shaft 15 carrying a wheel 16. Upon this same shaft 15 is a sprocket wheel 17 that is operated by a chain 19, and a corresponding sprocket wheel 18, the latter being journaled as at 20, in a cross-bar 21, that reaches from the underside of the table

12 to the standards 9. Mounted on this shaft 20, is an arm 22, the free end of which is provided with a segment 23, and each time this arm revolves about with the shaft 20, the segment 23 comes in contact with a segment 24, carried on a shaft 25, borne in bearings in the brace 21, and associated with this segment 24 is a needle-arm 26 returned by the force of gravity having a needle 27, so that as the two segments 23 and 24 coöperate, the needle will lift and the arm squeeze the bundle into shape for tying, while the cord is tensioned about the bundle and the knot tied by the knotter.

The knotter may be of any suitable kind, such, for instance, as that granted to one Charles Calahan, granted on June 7th, 1892, Number 476,519. In this knotter 28 represents the pivoted knotter jaw, for casting the cord to a knot making position, and 29 is its friction roller. A depression 30 is made in the upper portion of the jaw on a line with its pivot and extends in a plane parallel therewith to the outer point of said jaw. A flange 32 on the knotter for guiding the cord is provided, and there is also a cord guiding flange 33 that in its revolution forces the cord down on the finger 34. A knotter jaw 35 is rigid with a knotter 36 that is borne by a gear 37, and this gear is intermittently operated to turn the knotter at sequences, by a gear 38 carried by the wheel 16.

The cord 39 is placed into a cord holder 40, at the proper moment by a stroke of the needle, at which time teeth 41 on the wheel 16 will cause the cord holder to rotate, by passing into the notches 42 and this cord is delivered into a housing for the same designated by 44 so that as the needle 26 recedes from engagement with the knotter, a loop is formed into which to lay the next bundle. Thus, when the wheel 18 is operated, after placing the bundle, the needle will elevate and the wheel 16 will rotate until the teeth 38 come into contact with the teeth of the gear 37 when the knotter will take the cord from the needle and make the knot, after which the needle will drop back to its original position for repeating operation.

On the shaft 20 is an arm 43 to which is connected a link 46 and this link is connected to an ear 47 that depends from a movable cutter 48 that is adapted to coöperate with a stationary cutter 49, and each of these cutters is disposed upon graduated bars 50

and 51, so that they may be adjusted to vary the height of the bundle they are to trim. As the needle advances bringing the cord over the bundle, the cutter also advances at 5 a predetermined distance from the point of tying and this cutter chops the tops from the bundle and produces a trimmed bundle. Suitably associated with the shaft 15 is a counter 52, and each time this shaft rotates 10 and thus ties a bundle, the counting device is made to register the same. This may be done in any suitable manner, of course. In the present instance the counter may be actuated by a finger proceeding from the shaft 15. A cord box 53 is provided, and in association therewith is a tension device 54 and the cord proceeding therefrom is subject to such tension as will make the knotter form the knot close to the bundle, and thus 20 prevent the elements thereof from being lost. For the purpose of automatically and predeterminedly stopping the fly or treadle wheel 55, after each tying operation the periphery of wheel 55 is indented as at 63, into 25 which takes a beak 60, carried by a lever 61, having a foot piece 62. This lever 61 is pivoted to the frame 8, and bears on the beak 60 which is normally in position to catch the detent each time the wheel comes around. 30 When release is desired, the lever is lifted and the wheel is free for operation. For the purpose of operating the device the wheel 18 is harnessed to a wheel 55 through a chain 56, and this wheel if desired may be driven by pedals 57 from the operator who may be 35 provided with a seat 58.

The operation may briefly be stated as follows: The wheel 55 being operated starts wheel 18, also wheel 17, whereby arm 22 40 will cause the needle intermittently to operate and coöperate with the knotter, which in turn is being operated by wheel 17. The bundle is placed on the table, the needle arm 26 embraces it, the cord is tensioned about 45 the bundle and the coöperation of the needle, knotter and cord gives a properly tied bundle. During the entire operation the cord is under tension, and each successive operation causes the needle to advance and 50 retract to tie the bundle already placed and make room for the new one.

What I claim as new is:

1. A vegetable binding machine, comprising a table, a knotter mounted upon said table, means for operating the knotter, a needle shaft, a gravity controlled needle, an arm operating said needle, a segment on said needle shaft, a driving shaft, an arm revolv-

ing with said shaft, a segment carried by 60 said arm and engaging intermittently with the first named segment, and means for operating the shaft.

2. A vegetable binding machine comprising a table, a knotter mounted upon said table, means for operating said knotter, a needle shaft, a needle normally inoperative by gravity, an arm for operating said needle, a segment connected with said needle shaft, a driving shaft, an arm carried thereby, a segment carried by said arm and adapted to 70 coöperate with the segment on the needle shaft to intermittently operate the needle to cause it to coöperate with the knotter, and means to operate the shaft.

3. A vegetable binding machine comprising a table, a knotter mounted upon said table, means for operating the knotter, a needle shaft, a needle, a curved arm carrying said needle, a segment mounted on the needle shaft, a driving shaft, a wheel on said shaft, a treadle-wheel, a chain for transmitting motion from the last named wheel to the first named wheel, an arm on said shaft, a segment on said arm and adapted to coöperate with the segment on the needle shaft, 80 topping cutters adapted to operate to cut the tops from the bundles, means for operating the topping cutters, and means for holding the cord tight while the needle and the knotter operate.

4. A vegetable binding machine comprising a table, a knotter carried thereby, means for operating the knotter, a needle shaft, a gravity returning needle adapted to coöperate with the knotter, a curved arm for the 95 needle, and adapted to press the bundle together, a segment carried by said needle shaft, a driving shaft, means to operate said shaft, an arm revolving with the shaft, a segment carried by said arm, and coöperating with the needle shaft-segment to force the needle to an operative position, cutters operating to cut the tops from the bundles while the same are being tied, means for operating the cutters, and means to hold the 100 cord tight while the needle and knotter operate.

In witness whereof I have this 4th day of April, in the year nineteen hundred and thirteen, placed my name before two sub- 110 scribing witnesses.

CHARLES E. FERRELL.
